UNITED STATES PATENT OFFICE

DAVID A. JENKINS, OF KOKOMO, INDIANA, ASSIGNOR TO D. C. JENKINS GLASS COMPANY, OF KOKOMO, INDIANA, A CORPORATION

DESIGN FOR A BOWL

Application filed September 12, 1932. Serial No. 44,818. Term of patent 14 years.

To all whom it may concern:

Be it known that I, DAVID A. JENKINS, a citizen of the United States, residing at Kokomo, in the county of Howard, and State of Indiana, have invented a new, original, and ornamental Design for Bowl, of which the following is a specification, reference being had to the accompanying drawing, forming part thereof.

In the drawing, Figure 1 is a top plan view of a bowl, showing my new design, said bowl having a circular mouth of appreciable area, the diameter of which is greater than half that of any parallel diagonal across the bowl.

Fig. 2 is a side elevation of the bowl having a total height less than the diameter of the mouth, the body of the bowl including a plu-

rality of successive linearly connected substantially plain or flat sides, successive sides being of different depths and widths and diagonally opposite sides being substantially identical, the maximum depth of any side being greater than half the total height of the bowl, the bowl having a substantially flat bottom of an area at least as great as the mouth, and an outwardly directed rim at the mouth, the mouth and bottom being joined to the sides by globular-like portions, the sides and bottom being frustations of said portions.

I claim:

The ornamental design for a bowl substantially as shown and described.

DAVID A. JENKINS.
